UNITED STATES PATENT OFFICE.

LEVI KRIEG, OF FRANKFORT, INDIANA.

CARPET-STRETCHER.

SPECIFICATION forming part of Letters Patent No. 325,345, dated September 1, 1885.

Application filed May 16, 1885. (No model.)

To all whom it may concern:

Be it known that I, LEVI KRIEG, a citizen of the United States, residing at Frankfort, in the county of Clinton and State of Indiana, 5 have invented certain new and useful Improvements in Carpet-Stretchers; and I do hereby declare that the following is a full, clear, and exact description of the same, reference being had to the annexed drawing, 10 making a part of this specification, and to the letters and figures of reference marked thereon.

The present invention has relation to that class of carpet-stretchers consisting of a board, cross-head, or other like device having upon 15 its under side claws to enter the carpet, which is stretched by means of a windlass over which is wound a cord connected to the floor by a hook attached thereto, the windlass being provided with ratchet-wheels with which engage 20 pawls, and is operated by a pivoted lever having its end bifurcated and adapted to engage with the ratchets to turn the windlass.

The object of the present invention is to improve the above-mentioned class of carpet-stretchers and simplify their operation; and it 25 consists in forming the side arms of the bifurcation of the lever with elongated slots, through which the axle of the ratchet-wheel passes, so that the lever can be raised in a true vertical 30 line to disengage the dog in the bifurcation of the lever with the ratchet-teeth, also rendering the spring-pawl adjustable to regulate its pressure upon the ratchet-wheel, as will be hereinafter more fully described and claimed.

In the accompanying drawing, which represents a perspective view of my invention partly in broken section, A represents the bar, of any suitable length, having at its outer end 35 the cross-head B, provided upon its under side 40 with spurs a.

To the opposite end of the bar A are two short standards, b, between which is mounted upon a stationary shaft, c, a ratchet-wheel, C, having around its periphery a central groove, 45 d, for a cord or chain, e, one end thereof being attached to the wheel and the opposite end to a hooked rod, D, which passes through guides f in the bar and cross-head.

A lever, E, has a bifurcation at its lower 50 end which straddles the ratchet-wheel C, the side arms, g, of said bifurcation having elongated slots h, through which the axle c passes.

The lever E between the side arms, g, has a dog, i, to engage with the teeth of the wheel C, and back of said wheel is a spring-pawl, F, 55 longitudinally adjustable on the bar A by thumb-screw k, which passes through an elongated slot, l, into the bar. The end of the pawl F, as will be noticed, is notched, as shown at m, to allow the cord, wire, or chain e to 60 freely pass around the groove in the wheel C without catching on the end of the pawl. The adjustability of the pawl F is to allow it being brought with greater or less pressure against the ratchet-teeth, or to bring it out of 65 operative position.

In stretching the carpet the lever E is forced down until the dog i will readily engage with the teeth on the wheel C, after which the wheel can be turned by the lever. The hook in the 70 end of the rod D is driven in the floor, which acts as a fulcrum, and by turning the wheel in the proper direction the head B is forced forward with the carpet.

When it is desired to disengage the dog i 75 with the teeth in the wheel C, the lever is raised the extent of the slots h. Thus the head B is free to be moved forward to again take hold of the carpet.

The slotted side arms, g, of the lever E are 80 of importance, as they allow the said lever to be raised vertically to disengage the dog i with the ratchet-teeth, and by a downward pressure again made to engage therewith, the slight vertical movement being all that is required 85 of the lever to bring it in or out of operative position. The adjustability of the spring-pawl F is essential, as the pressure on the ratchet teeth is regulated to adapt the device in stretching carpets of different weights and 90 thickness, where a greater or less leverage power is required.

Any suitable means may be employed for connecting the rod D with the wheel C—such as a rope, cord, chain, or wire—and any suitable material may be used from which to construct the several parts of the stretcher.

Having now fully described my invention, what I claim as new, and desire to secure by Letters Patent, is—

In a carpet-stretcher, a grooved ratchet-wheel, a bifurcated lever having its side arms

formed with elongated slots, and a dog formed in the bifurcation to engage with the ratchet-wheel, the axle thereof extending through the slots and supported by standards, in combination with an adjustable spring-pawl, a cord and hook, and a bar and cross-head provided with spurs, substantially as and for the purpose set forth.

In testimony that I claim the above I have hereunto subscribed my name in the presence of two witnesses.

LEVI KRIEG.
